UNITED STATES PATENT OFFICE.

ANDREW H. WEIR AND CHRIS H. SMITH, OF EATON, OHIO.

WINDOW-SHADE BRACKET.

1,020,528.

Specification of Letters Patent. Patented Mar. 19, 1912.

Application filed July 11, 1911. Serial No. 637,873.

To all whom it may concern:

Be it known that we, ANDREW H. WEIR and CHRIS H. SMITH, citizens of the United States, residing at Eaton, in the county of 5 Preble and State of Ohio, have invented certain new and useful Improvements in Window-Shade Brackets, of which the following is a specification.

This invention relates to improvements in 10 shade roller and curtain brackets, and has for one of its objects to simplify and improve the construction and increase the efficiency and utility of devices of this character.

15 Another object of the invention is to provide a simply constructed device of this character which may be readily adjusted to fit window casings of varying lengths and which is also adapted to be attached to 20 door casings to support hangings or curtains.

With these and other objects in view, the invention consists of certain novel features of construction as hereafter shown and described.

The improved device may be applied to window casings, door casings or like openings, but for the purpose of illustration is shown applied to a conventional window 30 casing, and in the drawings thus employed for illustrating the invention: Figure 1 is a front elevation of a portion of a window casing with the improvement applied; Fig. 2 is a plan view of the improved device 35 with the casing in section on the line 2—2 of Fig. 1; Fig. 3 is a transverse section enlarged of the improved device on the line 3—3 of Fig. 2; Fig. 4 is a perspective view of the improved device detached; Fig. 5 is a 40 front elevation of a modified construction of the improved device; Fig. 6 is a transverse section on the line 6—6 of Fig. 4.

Corresponding and like parts are referred to in the following description and indicated 45 in all the views of the drawing by the same reference characters.

The improved device comprises in general two main body members slidably disposed one over the other, a holding device for supporting the shade roller and a bracket device for supporting a curtain pole. The several parts composing the improved device are formed with the main portions 50 curved transversely and with the same transverse curvature so that when superimposed the parts engage with each other at their

edges only, so that when the clamping devices are applied, the parts are firmly gripped together and rendered practically immovable.

60 The body portions of the improved device are represented respectively at 10—11 and are precisely alike and struck up from the same die and curved transversely, the transverse curvature thus being the same in both 65 of the members, the object to be hereafter explained.

At one end the member 10 is offset laterally as shown at 12, and provided with inwardly directed spurs 13, the latter extending in parallel relations to the member 10. The member 10 is also provided with a longitudinal slot 14. The member 11 is provided with a lateral offset 15, inwardly directed slots 16, and a longitudinal slot 17, 75 the two slots 14—16 registering when the plates are superimposed as shown. The shade roller brackets or holders are precisely alike except that one is provided with an open slot of the usual form to receive 80 the journals of the shade roller. The shade roller holder is represented as a whole at 18, and includes a base portion 19 which is curved transversely and is preferably struck up from the same die which forms the body 85 portions 10—11, the three parts 10—11—19 thus having the same transverse curvature. The curtain pole bracket is represented as a whole at 20, and includes a base portion 21 having the same curvature as the other 90 parts of the device. The base portions 19—21 are each perforated to receive a clamp bolt 22 having a clamp nut 23. By this simple arrangement when the parts 10—11—19—21 are superimposed and the 95 clamp bolt inserted through the apertures and the slots, the four parts may be firmly clamped together and engaged at their edges only, as illustrated in Fig. 3. This uniform curvature of the parts is an important 100 feature of the device and materially increases its efficiency and utility, as by this means the parts may be very firmly clamped together and all danger of loosening under the strains to which they are subjected when 105 in use, effectually prevented. In applying the improved device, the clamp nut 23 is loosened so that the members 10—11 may be adjusted longitudinally to adapt the device to the width of the casing represented at 24, and the spurs 13—17 forced into the edges 110 of the casing. The base members 19—21

are then adjusted upon the members 10—11 to adapt the holders 18—19 to the length of the shade roller. The clamp bolt is then tightened to firmly clamp the parts together, 5 the engaging edges of the uniformly curved members, as before stated, insuring the firm and rigid clamping of the parts. If the improved device is designed to be used only for a shade roller support, the bracket members 20—21 will be detached and the three parts 10—11—18 clamped together by the 10 bolts. If the device is to be employed for supporting curtain poles only, then the members 18—19 will be detached and the 15 members 10—11—20—21 only employed, and the clamp bolt utilized to support the parts in position.

In Figs. 5 and 6, a slight modification in the construction is shown comprising a 20 plate 25 having a longitudinal slot 26, and with perforated offsets 27 at the ends to receive the holding screws. In this modification the body portion 25 is transversely curved, preferably by the same die by which 25 the other members of the device are produced so that when the parts 18—19 and 20—21 are applied, and secured in place by the binding nut, the parts engage by their edges only, as shown in Fig. 6. By this arrangement the firm clamping of the parts is 30 insured in the same manner as heretofore described relative to the structure shown in Figs. 1, 2 and 3.

The device is simple in construction, can 35 be inexpensively manufactured as all the parts are struck up from sheet or plate metal, and so arranged that one single die

suffices for forming all of the parts which are arranged in engaging relations.

What we claim is:

1. A device of the class described comprising a plurality of members slidably disposed and curved transversely, the curvature of the plates being of the same radial lengths, means for connecting said members 45 to a window, a curtain roller support, and clamping means operating through said members and through said curtain roller support.

2. A device of the class described comprising plates slidably engaged and adapted to be connected to a window, a curtain roller support including a lateral base, said plates and lateral base being curved transversely with the same radial length, and 55 clamping means operating through said plates and base.

3. A device of the class described comprising plates slidably engaged and adapted to be connected to a window, a curtain 60 roller support including a lateral base, a curtain pole support including a vertical base, said plates, lateral base and vertical base being curved transversely with the same radial length, and clamping means operating through said plates and lateral base and vertical base.

In testimony whereof, we affix our signatures in presence of two witnesses.

ANDREW H. WEIR. [L. S.]
CHRIS H. SMITH. [L. S.]
